ULTRASONIC TRANSDUCER FOR A SPACE
ALARM SYSTEM FOR BURGLAR DETEC-
TION OR SIMILAR ARTICLE

Samuel M. Bagno, 18 Columbus Ave.,
Belleville, N.J. 07109

Filed Sept. 7, 1965, Ser. No. 86,879

Term of patent 14 years

(Cl. D26—14)

FIG. 1

FIG. 2

FIG. 3

FIG. 1 is a front elevational view of an ultrasonic transducer for a space alarm system for burglar detection or similar article showing my design;

FIG. 2 is a side view of the same; and

FIG. 3 is a rear view of the same.

I claim:

The ornamental design for an ultrasonic transducer for a space alarm system for burglar detection or similar article, substantially as shown.
